UNITED STATES PATENT OFFICE

99,554

DESIGN FOR A PADLOCK

Samuel C. Slaymaker, Lancaster, Pa., assignor to
The Slaymaker Lock Co., Lancaster, Pa., a cor-
poration of Pennsylvania

Application March 26, 1936, Serial No. 61,801

Term of patent 7 years

To all whom it may concern:

Be it known, that I, Samuel C. Slaymaker, a citizen of the United States, residing at Lancaster, in the county of Lancaster and State of Pennsylvania, have invented and produced a new, original, and ornamental Design for a Padlock, of which the following is a specification, reference being had to the accompanying drawing, forming a part thereof.

The novel features of the design reside in the front face plate or section of rectangular shape having a raised or embossed border line and vertical stepped bars in the lower corner thereof,

combined with the casing of the configuration shown.

In said drawing:

The figure is a front perspective view of a padlock, showing my new design. The back of the lock is plain.

I claim:

The ornamental design for a padlock, substantially as shown and described.

In testimony whereof I have hereunto subscribed my name in the presence of two attesting witnesses.

SAMUEL C. SLAYMAKER.
